UNITED STATES PATENT OFFICE.

GUSTAV H. GENRICH, OF DORCHESTER, WISCONSIN.

SLEIGH-KNEE.

987,713.

Specification of Letters Patent. Patented Mar. 28, 1911.

Application filed April 25, 1910. Serial No. 557,444.

To all whom it may concern:

Be it known that I, GUSTAV H. GENRICH, a citizen of the United States, residing at Dorchester, county of Clark, and State of Wisconsin, have invented certain new and useful Improvements in Sleigh-Knees, of which the following is a specification.

My invention relates to sleigh knees and has for its object the production of a device 10 of this character which will be of such improved construction and so connected to the body of the sleigh as to permit of oscillatory movement of said knees and hence of the runners attached thereto, and to thereby 15 facilitate the latter to follow or to adapt themselves to the surface of the ground traveled over notwithstanding the roughness or undulatory character thereof.

A further object is the provision of a 20 sleigh knee which will be of durable and economical construction and efficient in operation.

Other objects will appear hereinafter.

With these objects in view my invention 25 consists in a sleigh knee characterized as above mentioned and in certain details of construction and arrangement of parts all as will be, hereinafter fully described and more particularly pointed out in the appended claims.

My invention will be more readily understood by reference to the accompanying drawing forming a part of this specification, and in which,

35 Figure 1 is a perspective view of a sleigh runner and cross beam to which is applied a sleigh knee embodying the preferred form of my invention, Fig. 2 is a side elevation of the knee attached to the sleigh runner and 40 cross beam, Fig. 3 is an end elevation thereof, Fig. 4 is a sectional detail taken on line $x-x$ of Fig. 5, and Fig. 5 is a transverse section taken on line $y-y$ of Fig. 4.

Referring now to the drawing, 1 indicates 45 a sleigh runner which may be of any ordinary or preferred design, and 2 the cross beam of the sleigh.

3 indicates the knee standard, the divergently disposed legs 4 of the latter being 50 channeled at their lower extremities for snug embracing of the runner 1 to which said extremities are secured by means of bolts 5 and nuts 6. With a view of conducing toward lightness and durability in 55 the legs 4, the same, as seen, are preferably comparatively thin the same being formed

with integral longitudinally extending stiffening or reinforcing ribs 7. The upper end of said knee standard terminates in a transversely inwardly extending arm 8 in the upper side of which are formed knuckles 9 and an intermediate recess 10.

Secured at its extremities by bolts 11 and nuts 12 to the under side of the beam 2 is a plate 13; the latter, in order to form a more rigid connection with said beam, being provided at its longitudinal edges with upwardly extending integral flanges 13' which embrace the opposite longitudinal sides of said beam. Formed upon and depending from the under side of the plate 13 intermediate its extremities are knuckles 14, the same being spaced to snugly receive therebetween the upper extremity or arm 8 of the knee standard 3. A hinge pin or bolt 15 extends through alining circular slots provided in the knuckles 9 and 14, it being locked in position therein by means of a head 16 formed at one extremity thereof and by a nut 19 threaded upon the opposite end thereof. Formed upon the plate 13 intermediate the knuckles 9, the same depending into the recess 10 in the arm 8 is an elongated lug 18, the under concaved side thereof resting upon the upper side of the bolt 15; and formed upon the upper extremity of said standard intermediate the knuckles 14 is a similarly formed and upwardly projecting lug 19 concaved at its upper side for engagement of the under side of said bolt. 90 The adjacent surfaces of the portions 18 and 19 are separated somewhat and the same are divergently disposed, as clearly shown in Fig. 5, in order to permit of a certain degree of oscillatory movement of the knee standard. Formed at the inner extremity of the plate 13 is an eye 20. A brace rod 21 is secured at its rearward extremity to said eye, the same extending forwardly therefrom and being connected at its forward extremity with the nose of the runner.

With a construction as set forth it will be seen that an efficient and economical connection of the runner with the body is provided, and further a connection which will 105 permit of oscillatory movement of the runners so as to adapt the latter for travel over roads whatever be their character.

While I have shown what I deem to be the preferable form of my sleigh knee, I do 110 not wish to be limited thereto as there might be various changes made in the details of

construction and arrangement of parts described without departing from the spirit of the invention comprehended within the scope of the appended claims.

6 Having described my invention what I claim as new and desire to secure by Letters Patent is:

1. The combination with a sleigh beam and runner, of a knee standard secured at its bottom to said runner, a transversely extending arm formed at the upper extremity of said standard, upwardly extending knuckles formed upon said arm, a plate secured to the under side of said beam having depending 15 knuckles formed thereon interjacently positioned with the before named knuckles, a pin extending through and connecting the sides of said knuckles and projecting lugs formed on adjacent surfaces of said standard 20 arm and said plate between said loop and concaved to engage respectively the lower and upper sides of said pin, substantially as described.
2. The combination with a sleigh beam and runner, of a knee connecting said beam and runner, said knee comprising a standard, said standard having a bifurcated divergent base portion, the lower extremity of said base portion being channeled for engagement 25 of said runner, securing devices connecting said extremity of said base portion and said runner, a transversely extending arm formed at the upper extremity of said standard, upwardly extending knuckles 30 formed upon said arm, a plate secured to the under side of said beam having depending knuckles formed thereon interjacently positioned with the before-named knuckles, a pin extending through and connecting the sets of said knuckles, and projecting lugs formed on the adjacent surfaces of said plate, and said standard arm intermediate the knuckles formed upon said surfaces, said lugs engaging respectively the upper and 35 lower sides of said pin, the adjacent surfaces of said lugs being spaced to permit of oscillation of said knee standard, substantially as described.

pin extending through and connecting the sets of said knuckles, and projecting lugs formed on adjacent surfaces of said standard arm and said plate engaging respectively the lower and upper sides of said pin, substantially as described.

3. The combination with a sleigh beam and runner, of a knee connecting said beam and runner, said knee comprising a standard, said standard having a bifurcated divergent base portion, the lower extremity of said base portion being channeled for engagement 45 of said runner, securing devices connecting said extremity of said base portion and said runner, a transversely extending arm formed at the upper extremity of said standard, upwardly extending knuckles 50 formed upon said arm, a plate secured to the under side of said beam having depending knuckles formed thereon interjacently positioned with the before-named knuckles, a pin extending through and connecting the sets of said knuckles, and projecting lugs formed on the adjacent surfaces of said plate, and said standard arm intermediate the knuckles formed upon said surfaces, said lugs engaging respectively the upper and 55 lower sides of said pin, the adjacent surfaces of said lugs being spaced to permit of oscillation of said knee standard, substantially as described.

In testimony whereof I have signed my name to this specification in the presence of two subscribing witnesses.

GUST. H. GENRICH.
